UNITED STATES PATENT OFFICE.

BRYANT H. BLOOD, OF HARTFORD, CONNECTICUT, ASSIGNOR TO PRATT & WHITNEY COMPANY, OF NEW YORK, N. Y., A CORPORATION OF NEW JERSEY.

DESIGN FOR A GAGE-BLOCK.

54,584.

Specification for Design.

Patented Mar. 9, 1920.

Application filed June 28, 1919. Serial No. 307,482. Term of patent 14 years.

To all whom it may concern:

Be it known that I, BRYANT H. BLOOD, a citizen of the United States, residing at Hartford, in the county of Hartford and State of Connecticut, have invented a new, original, and ornamental Design for Gage-Blocks, of which the following is a specification, reference being had to the accompanying drawing, forming a part thereof.

Of the drawing:

Figure 1 is a perspective view of a gage block embodying my new design.

Fig. 2 is a plan view.

Fig. 3 is an enlarged fragmentary sectional view taken along the line 3-3 of Fig. 2.

Referring to the drawing, it will be ob-

served that the parallel end surfaces of the gage block are highly polished and that the lateral surfaces are provided with a dull finish, preferably secured by the process known as mud blasting. The small corner surfaces are polished, thus offering a striking contrast to the dull finish of the main lateral surfaces. As indicated in Fig. 3, the corners of the blocks where the bright end surfaces and the dull lateral surfaces join are rounded.

I claim:

The ornamental design for a gage block as shown and described.

In testimony whereof I hereto affix my signature.

BRYANT H. BLOOD.
